SOLDERING IRON HOLDER

William H. Myers, 1121 McReynolds NW,
Grand Rapids, Mich.

Filed Mar. 21, 1963, Ser. No. 74,077

Term of patent 14 years

(Cl. D26—1)

The FIGURE is a perspective view of a soldering iron holder showing my new design.

The back face of the soldering iron holder is flat and unornamented. The broken line showing of a soldering iron is for illustrative purposes only. The characteristic feature of my design for a soldering iron holder resides in the combination on a rectangular base with an integral rear wall having a sloping front face with a tubular socket centered thereon, and a tubular, clip retained, iron wiper on the forward end of the planar surface, all as shown.

I claim:

The ornamental design for a soldering iron holder, as shown and described.
